UNITED STATES PATENT OFFICE

128,213

DESIGN FOR A TEXTILE FABRIC

Edward McLaughlin, South Bound Brook, N. J.

Application June 19, 1941, Serial No. 101,555

Term of patent 3½ years

To all whom it may concern:

Be it known that I, Edward McLaughlin, a citizen of the United States, residing in South Bound Brook, in the county of Somerset and State of New Jersey, have invented a new, original, and ornamental Design for a Textile Fabric, of which the following is a specification, reference being had to the accompanying drawing, forming part thereof.

Fig. 1 is a plan view of a textile fabric showing my new design, and

Fig. 2 is the reverse side thereof.

I claim:

The ornamental design for a textile fabric, substantially as shown.

EDWARD McLAUGHLIN.
